CLAIM

The ornamental design for a skid shoe as shown and described.

DESCRIPTION

FIG. 1 is a top, front perspective view of a skid shoe showing our new design;

FIG. 2 is a top, rear perspective view thereof;

FIG. 3 is a bottom, front perspective view thereof;

FIG. 4 is a bottom, rear perspective view thereof;

FIG. 5 is a top, front view thereof;

FIG. 6 is a front view thereof;

FIG. 7 is a rear view thereof;

FIG. 8 is a left side view thereof;

FIG. 9 is a right side view thereof;

FIG. 10 is a top plan view thereof; and,

FIG. 11 is a bottom plan view thereof.

The broken lines in the drawings are included for purposes of illustrating portions of the skid shoe which form no part of the claimed design.

1 Claim, 8 Drawing Sheets(56)
